ASH TRAY

Robert S. McDorman, 944 Liggett Blvd., Crestwood, Mo.

Filed Aug. 5, 1963, Ser. No. 76,089

Term of patent 14 years

(Cl. D85—2)

FIG. 1

FIG. 2

FIG. 3

FIG. 1 is a perspective view of an ash tray embodying my new design;

FIG. 2 is a reduced-scale top plan view thereof; and FIG. 3 is a reduced-scale bottom plan view thereof.

The ash tray is shaded to show textural contrast rather than color contrast.

I claim:

The ornamental design for an ash tray, substantially as shown and described.
